No. 884,925.

PATENTED APR. 14, 1908.

I. W. HERMAN.

LATCH.

APPLICATION FILED JUNE 19, 1907

UNITED STATES PATENT OFFICE.

IGNATIUS W. HERMAN, OF COTESFIELD, NEBRASKA.

LATCH.

No. 884,925.

Specification of Letters Patent.

Patented April 14, 1908.

Application filed June 19, 1907. Serial No. 379,736.

To all whom it may concern:

Be it known that I, IGNATIUS W. HERMAN, a citizen of the United States, and a resident of Cotesfield, in the county of Howard and State of Nebraska, have invented a new and Improved Latch, of which the following is a full, clear, and exact description.

This invention has reference to improvements in latches, the object of which is not only to provide a means for securing a door in closed position, but also to guard against accidental displacement of the locking-bar or member, whereby the door is permitted to freely swing open. A latch having this feature of advantage embodying the simplicity of construction of the present invention, is of special value to farmers and others for barn-doors, feed-doors, etc. where it is necessary that the door be so secured that a shrewd animal will be unable to dislodge the locking member.

Reference is to be had to the accompanying drawings forming a part of this specification, in which similar characters of reference indicate corresponding parts in all the figures.

Figure 1 is a face view of my improved latch as applied to a door, the latch being shown partly in section; Fig. 2 is an end view 30 of the latch; Fig. 3 is a cross section of the same on the line 3—3 of Fig. 1; Fig. 4 is a perspective view of a dog which operates to lock the latching bar in place; Fig. 5 is a perspective view of the latching bar as used in 35 connection with sliding doors; and Fig. 6 is a like view of a latching bar for hinged doors.

The preferred form of my improved latch includes a casing 1 which is U-shaped in cross section and of tapering form longitudinally, 40 with the enlarged portion of the casing being arranged at the forward end of the latch and the bottom edge thereof disposed substantially horizontal. This casing is bolted or otherwise secured to the door through the 45 projecting flanges, as shown, and is provided with a longitudinal slot 2 formed intermediate its length in the front thereof, said slot having a downwardly-directed arm or notch 2^a at its forward end. The slot 2 and its 50 notch 2^a, when the latch is applied, are also reproduced in the door and in a plate 3 secured to the opposite side of the door.

Slidably fitting within the casing 1, is a latching bar 4 through which passes a pin or bolt 5 also passing through and guided in the

slot 2 and the corresponding slot in the door and plate 3. Adjacent to the casing 1 at the outside of the slot 2, the pin 5 is provided with an operating knob 6, and at its opposite end with a head or other enlargement 7, whereby the latching bar 4 may be easily slid back and forth within the casing at either side of the door and retained against direct sliding movement when the pin 5 is passed into the notch 2^a. The forward free end of the latching bar 4 has a notch 8 formed on its under edge designed to be engaged with the lower offset portion of a U-shaped keeper 9 which is bolted or otherwise secured to the door-jamb. Pivotally suspended within this keeper above the latching member, is a dog 10 shown in detail in Fig. 5, the same preferably consisting of a block having at one edge a finger or projection 11 which is adapted to contact with one edge of the keeper 9 when the dog is swung downwardly, and thereby provide a stop and also serving as a handle for throwing the dog to inoperative position. By this construction, when the latching bar is shifted to the forward limit of its movement and engaged with the keeper 9 and the dog 10 thrown downwardly, it is impossible to accidentally displace the latching bar, nor can the same be displaced by the shrewdest animal, making the invention especially desirable for barn - doors, feed - doors and in many other relations.

The latching bar when slid from the keeper will tend to stay in place in view of the inclination of the slot 2, which is parallel to the top edge of the casing. In using the latch on hinged doors it will be unnecessary to construct the latching bar 4 with a notch 8, but the same should have a plain outer end as shown in Fig. 6. With this form of latching bar the casing may be narrower and the notch 2^a, leading from the slot 2, shorter.

The latch as shown and described, although being my preferred, practical embodiment of the invention, is obviously, nevertheless, susceptible of numerous modifications falling within the scope of the annexed claims.

Having thus described my invention I claim as new and desire to secure by Letters Patent:

1. A latch comprising a casing longitudinally tapered and U-shaped in cross section, having a longitudinal slot formed in the face thereof substantially parallel to the top edge 110

of the casing and provided with a projection leading downwardly from the inward end of said slot, a latching bar within the casing, having a notch formed in its forward end, a keeper, a dog pivoted above the latching-bar within the keeper, having a finger at one side, and means connected with the latching-bar and passing through said slot for shifting the latching bar into and out of engagement with

10 said keeper.

2. A latch, comprising a longitudinally tapered casing having a slot in its front face substantially parallel to its top edge with a downwardly directed notch at the forward 15 end of the slot, a keeper, a latching-bar fitting the small end of the casing, and a handle

connected with the latching-bar through said slot for shifting it to and from the keeper.

3. A latch comprising a casing having a slot in its front face inclined upwardly in a 20 forward direction, and a bolt slideable in said casing having an operating device passing through said slot, whereby the bolt under the influence of gravity tends to remain in a retracted position. 25

In testimony whereof I have signed my name to this specification in the presence of two subscribing witnesses.

IGNATIUS W. HERMAN.

Witnesses:

EMIL S. LIND,

HARRY ROLLINS DE LAND.
